TRACK CLEARING DEVICE

Filed Nov. 3, 1928

Inventor:

Vincent Ciriello

By *Clarence A. O'Brien*, Attorney

UNITED STATES PATENT OFFICE

VINCENT CIRIELLO, OF READVILLE, MASSACHUSETTS

TRACK-CLEARING DEVICE

Application filed November 3, 1928. Serial No. 316,990.

This invention relates to new and useful improvements in devices for clearing trackways of snow, ice and the like, and aims to provide a high speed burner unit adapted to 5 be associated with a flat car movable upon the track and whereby the burner unit may be directed by the workman to any point upon or adjacent the track to melt all snow and ice therefrom, and especially at the switch 10 point.

An important object of the invention is to provide a device of this character that is extremely simple in construction and inexpensive to manufacture, and one that may be operated at minimum expense.

With the foregoing and other objects in view as the nature of the invention will be better understood, the same comprises the novel form, combination and arrangement of 20 parts to be hereinafter more fully set forth and claimed.

In the accompanying drawings wherein like reference characters indicate corresponding parts throughout the same:

25 Figure 1 is a side elevational view of the improved burner unit.

Figure 2 is a fragmentary longitudinal view, taken substantially upon the line 2-2 of Figure 1.

30 Figure 3 is a sectional view, through a union or coupling that comprises an essential feature of the burner unit.

As intimated in the statement of invention, my improved burner is adapted to be 35 used in conjunction with a mobile track clearer for melting snow and ice accumulated on the track or adjacent thereto. As is well known in the art, such track cleaners usually embody a platform movable on the track and 40 on the car is mounted a suitable fuel tank, the contents of which may be discharged therefrom by air under pressure to be conveyed through one or more suitable conduits, which conduits, at their free ends, are provided with burner units for directing a flame 45 against the track for melting the accumulation of snow or ice. In the present illustrated embodiment of the invention, the burner unit is designated generally by the reference character 50 12, and is adapted to be connected with

one end of the aforementioned flexible conduit in a manner hereinafter made manifest. The burner unit 12 consists of an elongated fuel conveying pipe 12', one end of which is adapted to be coupled to the free end of a flexible fuel conduit (not shown), and leading from a suitable source of supply (not shown), and adjacent its free end, said pipe 12' merges into a coil 13. The outer end convolute of the coil 13 merges into a substantially straight rearwardly extending portion, 55 said portion extending substantially parallel to the coil, and at its free end terminates substantially parallel to the fuel conducting pipe 12' as shown to advantage in Figure 1. An elbow coupling 14 is attached to the free end of the straight portion of the endmost coil, while a pipe 15 has one end threaded into the coupling 14 and at its other end is suitably coupled to a pipe 16, the last mentioned pipe 16 60 extending forwardly through and arranged concentrically within the coil 13 as is also shown to advantage in Figure 1. Located upon the forward end of this nozzle pipe 16 is a suitable burner tip 17, which burner tip 17 65 terminates inwardly from the adjacent end of the coil 13, as shown to advantage in Figure 1. Obviously by reason of the location of this tip the flame therefrom will create heat 70 within the coil 13 for substantially vaporizing the fuel flowing through said coil.

The intake pipe of the coil designated 12' is equipped with a control valve 19, while associated with the inner end of this pipe and extending forwardly and diagonally with respect thereto is a brace pipe 20, the forward end of which is associated with the said coupling 14, see Figure 10. Between this brace pipe 20 and the pipe 12' of the burner unit is a transverse brace pipe 21.

In view of the foregoing description when considered in conjunction with the accompanying drawing it will be apparent that I have provided a novel, simple and useful track cleaner that is well adapted for all the purposes heretofore designated, even though I have herein shown and described the invention as consisting of certain detail structural elements it is nevertheless to be understood that minor changes may be made therein 100

without departing from the spirit of the invention or the scope of the appended claims.

Having thus described the invention, what I claim as new and desire to secure by Letters Patent is:

- 5 1. In a burner of the character described, an elongated fuel conveying pipe, said pipe being adapted to be connected at one end to a suitable source of fuel supply, said pipe adjacent its opposite end merging into a coil, the forward convolute of said coil terminating in a straight extending portion extending exteriorly of and in parallelism to said coil, a second fuel conveying pipe extending 10 through the coil and arranged concentrically therein, a burner tip on one end of said second mentioned fuel conveying pipe, a pipe connected at one end to the other end of said second fuel conveying pipe, said pipe at its 15 opposite end connected to the terminal of the said extending portion of said forward convolute, a coupling member connecting said opposite end of the last mentioned pipe to the terminal of the coil extension, a brace 20 pipe extending from said coupling member, and secured to the first mentioned fuel conveying pipe, at its free end, at a point remote from said coil, and a second brace member secured at one end to the first mentioned fuel conveying pipe, and at its opposite end to the first mentioned brace member, said second brace member constituting 25 a handle for the burner.
2. In a burner of the class described, an elongated fuel conveying pipe, a coil at the forward end of said pipe, a second fuel conducting pipe extending longitudinally through the center of the coil and having communication with the foremost convolute 30 of the coil, a burner tip located upon the forward end of said longitudinally extending fuel conducting pipe inwardly from the adjacent end of said coil, a brace pipe secured at one end to the first mentioned fuel 35 conducting pipe remote from the coil, means for securing the other end of said brace pipe to the coil rearwardly of the coil, and a transversely extending brace member between the brace pipe and the first mentioned fuel conducting pipe, to provide a handle for the burner.

In testimony whereof I affix my signature.

VINCENT CIRIELLO.
